UNITED STATES PATENT OFFICE.

JOSEPH C. HAMMOND, JR., OF ROCKVILLE, AND THEODORE E. KING, OF WESTPORT, CONNECTICUT.

SHOE-CLASP.

SPECIFICATION forming part of Letters Patent No. 334,434, dated January 19, 1886.

Application filed May 15, 1885. Serial No. 165,569. (No model.)

To all whom it may concern:

Be it known that we, JOSEPH C. HAMMOND, Jr., of Rockville, in the county of Tolland and State of Connecticut, and THEODORE E. KING, of Westport, in the county of Fairfield, and said State, have invented certain new and useful Improvements in Shoe-Clasps, of which the following is a description, reference being had to the accompanying drawings, where—

10 Figure 1 is a view of one form of our improved tongue-frame and tongue. Fig. 2 is a plan view of the clasp. Fig. 3 is a front end view of the form of clasp shown in Fig. 1. Fig. 4 shows an alternate form of our improved tongue-frame and tongue. Fig. 5 is a plan view of the form shown in Fig. 4. Fig. 6 is a front end view of the latter. Fig. 7 is a view in section of the strap, and in end view of the frame of the device shown in Fig. 4.

20 The within-described improvement relates to the class of buckles and clasps which are adapted for use on various articles of wearing-apparel; but it is more particularly intended for use on "arctic" overshoes; and it consists in 25 the improved tongue and tongue-frame, each bent to shape from a single piece of wire, and having the co operating locking and fastening features, formed in the bending of the wire to shape, and aiding in holding the tongue closed, 30 and in other details of the device, as more particularly hereinafter described, and pointed out in the claims.

In the accompanying drawings, the letter *a* denotes a tongue-frame formed of wire that is 35 doubled back upon itself, with the offset and curved part *b* bent into the side and bearing between the two parts of the wire the socket *c* for the tongue-pivot. These sockets are formed opposite to each other in the parallel 40 sides *a'* of the frame, and at some distance back from its open end.

The tongue *d* is formed of a single piece of wire, hook shape, with trunnions *d'*, turned in opposite directions and adapted to fit in the 45 pivot-sockets *c* and form a pivot upon which the tongue swings.

In the form of tongue and frame shown in Figs. 1 to 7, the projections *e* from the broadened part of the tongue take into sockets *e'*,

formed in folding the tongue-frame, and hold 50 the tongue against accidental opening when closed. By lifting upon the point of the tongue these locking shoulders or projections are readily passed between the obstructing frame by reason of the elasticity of the tongue, 55 which allows it to yield to inward pressure upon the opposite shoulders, and this is also aided by the outward spring of the frame.

The alternate form of tongue and frame (shown in Figs. 4 to 7) is also formed by bending the respective parts to shape from a single piece of wire; but the ends of the tongue-frame, instead of being inturned and meeting the ends of the cross-bar of the frame, are sharpened and turned downward at the corners of 65 the frame in points *f*, which serve as means for fastening the parts to the strap or like part of the article on which the clasp is to be used, as by pushing them through and clinching them, as shown in Fig. 7.

We claim as our invention—

1. In combination, in a clasp, a tongue-frame formed of a single piece of wire bent to the form of the open frame, substantially as described, with sockets for supporting pivotal and locking projections on the tongue, and a tongue formed of a single piece of wire bent to shape, with pivots and projections adapted to fit the respective sockets, all substantially as described.

2. In combination, in a clasp, a tongue-frame, *a*, formed of a single piece of wire bent to shape, with pivot-sockets *c*, and locking-sockets, and the ends of the wire sharpened and turned downward from the plane of the 85 frame, and a tongue, *d*, with pivots *d'*, and locking-projections *e*, all substantially as described.

JOSEPH C. HAMMOND, JR.
THEODORE E. KING.
